UNITED STATES PATENT OFFICE

2,578,039

TANK FOR USE IN IMPREGNATING WOOD

Gordon H. Bonnell, Arthur J. Bailey, and Gardner G. Garlick, Kalamazoo, Mich., assignors to Protection Products Manufacturing Company, Kalamazoo, Mich.

Original application November 21, 1946, Serial No. 711,436. Divided and this application February 12, 1948, Serial No. 7,825

8 Claims. (Cl. 21—65)

1

This invention relates to improvements in a tank for use in impregnating wood.

The present application is a division of the applicants' application for Letters Patent filed November 21, 1946, Serial No. 711,436, and now abandoned.

The main objects of this invention are:

First, to provide a tank for use in impregnating wood and the like which is well adapted to withstand external pressures resulting from vacuums created within the tank.

Second, to provide an impregnating tank in which the bottom and wall panels and the top may be formed of relatively light sheet stock and are so supported as to withstand stresses incident to a high vacuum produced within the tank.

Third, to provide a structure of this character in which the cover is urged to closed position by the vacuum within the tank, thus avoiding the necessity of cover retaining or clamping means.

Fourth, to provide a structure having these advantages which is quite simple and economical.

Further objects relating to details and economies of the invention will appear from the description to follow. The invention is defined in the claims. The drawings, of which there are two sheets, illustrate a preferred form of our structure, in which:

Fig. 1 is a fragmentary side elevational view of a structure embodying our invention, partially broken away and partially in longitudinal section.

Fig. 2 is an enlarged fragmentary view in transverse section on line 2—2 of Fig. 1 illustrating structural details of the tank and also of the cover and its mounting.

Fig. 3 is an enlarged transverse section on a line corresponding to line 3—3 of Fig. 1.

Fig. 4 is an enlarged fragmentary view in horizontal section on a line corresponding to line 4—4 of Fig. 3.

Fig. 5 is an enlarged fragmentary view in section on line 5—5 of Figs. 3 and 4.

The structure illustrated in the accompanying drawing is particularly designed by us for use in the practice of the method of our above identified original application for the impregnation of wood or lumber in substantial quantities and lengths, a charge of lumber indicated conventionally at 1 being shown within the tank of our present invention designated generally by the numeral 2. The tank is designed to receive a suitable quantity of impregnating liquid and connections 3 and 4 are conventionally illustrated,

2

the connection 4 being a liquid connection. The tank is provided with sight gages 5 to facilitate determination of the depth of impregnating liquid within the tank. The tank is especially designed to withstand external pressures or stresses resulting from atmospheric pressures when a vacuum is created within the tank. Also, to effectively support the charge of material to be treated.

10 The tank comprises a bottom frame consisting of side and end members 6 of angle section disposed with the angles facing inwardly and upwardly, and a top frame comprising side and end members 7 disposed with their angles facing outwardly and downwardly. Corner uprights 8 connect these top and bottom frames. These corner uprights comprise outer members 9 of angle section disposed with their angles facing inwardly and inner members 10 of angle section disposed with their angles facing outwardly, that is, upright members being in facing relation and the flanges thereof welded together.

15 The side and end reinforcing ribs 11 are arranged on the inner sides of the wall panels 12 which in the embodiment illustrated are of a suitable gage of sheet metal having their edges welded to the top and bottom frames throughout to provide air-tight connection between the wall panels and the frame members. The wall panels are also welded to the reinforcing ribs as indicated at 13. The reinforcing ribs 11 are of T section.

20 The bottom panel 14 is also of sheet metal and its edges are welded to the edges of the bottom frame members as indicated at 15. The bottom reinforcing ribs 16 are likewise of T section and the bottom panel 14 is welded thereto. The bottom ribs are disposed between opposed pairs of upright side ribs and are welded thereto as indicated at 17. Angled foot or bracket members 18 are provided for further securing the end ribs members to the end members of the bottom frame and to the panel as indicated at 19 and 20, Fig. 5.

25 The side walls are provided with diagonally disposed braces 21 of which are disposed externally and welded together at their meeting of crossing points 210 and also welded to the corner uprights at 22.

The load or charge indicated by dotted lines 30 is supported by bars 23 arranged between opposed upright side ribs and welded thereto as indicated at 24. These supports are arranged in an inclined series, being inclined toward the connection 3 so that the load is supported in an inclined 35 relation within the tank, which facilitates drain-

ing of the load. The side ribs serve as side abutments for the charge of material, that is, they receive the thrust of the material when it is being lowered into or removed from the tank. The load is preferably introduced and removed from the tank by means of a hoist after the load has been bound together or assembled as a unit, and consequently there is likely to be a swaying movement of the load, but the structure is such as to effectively withstand such shocks or thrusts.

The cover designated generally by the numeral 25 comprises the cover frame 26 formed of side and end members of angle section arranged to face downwardly and outwardly with the horizontal flanges 27 thereof over hanging the top flange 28 of the top frame of the tank. This top flange 28 serves as a cover jamb. The gasket 29 is arranged on the jamb or cover seat, the cover resting on the gasket. The cover panel 30 is secured to the cover frame by welding thereto as indicated at 31 and 32, and is rigidly reinforced by longitudinal and transverse reinforcing members 33 and 34. The cover is centered on the tank by means of the positioning studs 35 which are desirably in the form of bolts adjustably secured to the depending flanges 36 of the cover frame.

The threaded studs or bolts 35 are provided with adjusting and clamping nuts 37 coacting with the cover frame flanges 36. In the embodiment illustrated, the cover is swingably secured to the tank by means of hinges consisting of the bolt-like elements 38 which are pivoted at 39 to the ears 40 provided thereon on the tank. These bolts extend loosely through ears 41 provided on the cover, the bores 42 receiving the bolts being of such size as to allow free vertical movement of the cover relative to its hinge elements. This permits the swinging of the cover by means of the cable 44, having branches 45 engageable with the eyes 46 on the cover. This permits the swinging of the cover to open and closed position and at the same time permits vertical movement of the cover when in closed position. The cover is preferably provided with a hold-down member 47 adapted to engage the material treated when the cover is closed and hold it in submerged relation to the liquid. With this arrangement of the parts, the tank may be made of comparatively light materials, but it is at the same time capable of withstanding external pressure resulting from high degree of vacuum therein. In fact, it is designed to withstand pressures up to a complete vacuum. No hold-down or locking means are required for the cover as it is held down by the pressure resulting from the vacuum within the tank.

The tank of our invention is especially designed by us for use in the practice of the method of our said application, Serial No. 711,436. It is desirable, however, for use in other relations where it is desired to treat materials in a substantial degree of vacuum. Another advantage is that as the pressures are external, the framing and ribbing support for the walls is interiorly arranged, leaving the exterior of the tank comparatively free from projecting parts.

We have illustrated and described our invention in a highly practical embodiment thereof. We have not attempted to illustrate or described other embodiments or adaptations, as it is believed that this disclosure will enable those skilled in the art to embody or adapt our invention as may be desired.

Having thus described our invention, what we

claim as new and desire to secure by Letters Patent is:

1. In a tank for impregnating materials, the combination of bottom frame side and end members of angled section disposed with their angles facing inwardly, top frame side and end members of angled section disposed with their angles facing outwardly, the top frame constituting a cover gasket seat, corner uprights extending from said top and bottom frame members and comprising facing pairs of angle section welded together at their edges, a plurality of side and end ribs of I section disposed in spaced relation with their ends in abutting relation to the horizontal flanges of the top and bottom frame members and welded thereto, bottom ribs of I section disposed with their ends abutting the lower ends of the side ribs and welded thereto, bottom side and end wall panels disposed on the outer sides of the bottom, side and end ribs and with their edges in abutting relation to the bottom and top frame members and corner uprights and welded thereto, diagonally disposed reinforcing and supporting bars arranged on the outer sides of the side wall panels, a cover comprising downwardly and outwardly facing side and end frame members of angle section, a cover panel arranged on said frame members, longitudinal and transverse reinforcing bars arranged on the outer side of said cover panel, hinge members carried by said tank and having a swinging element extending slidably through said cover to form a slip connection to said cover whereby the cover is supported for swinging and for vertical movement relative to the top frame of the tank, and adjustable positioning studs on said cover coacting with said tank top frame.

2. In a tank for impregnating materials the combination of bottom frame side and end members of angled section disposed with their angles facing inwardly, top frame side and end members of angled section disposed with their angles facing outwardly, the top frame constituting a cover gasket seat, corner uprights extending between said top and bottom frame members, a plurality of side and end ribs of I section disposed in spaced relation with their ends in abutting relation to the horizontal flanges of the top and bottom frame members and welded thereto, bottom ribs of I section disposed with their ends abutting the lower ends of the side ribs and welded thereto, bottom side and end wall panels disposed on the outer sides of the bottom, side and end ribs with their edges in abutting relation to the bottom and top frame members and corner uprights and welded thereto, a cover comprising downwardly and outwardly facing side and end frame members of angle section, a cover panel arranged on said frame members, longitudinal and transverse reinforcing bars arranged on the outer side of said cover panel, hinge members carried by said tank and having a swinging element extending slidably through said cover to form a slip connection to said cover whereby the cover is supported for swinging and for vertical movement relative to the top frame of the tank, and adjustable positioning studs on said cover coacting with said tank top frame.

3. In a tank for impregnating materials, the combination of bottom frame side and end members of angled section disposed with their angles facing inwardly, top frame side and end members of angled section disposed with their angles facing outwardly, the top frame constituting a

cover gasket seat, corner uprights extending between said top and bottom frame members, a plurality of side and end ribs of I section disposed in spaced relation with their ends in abutting relation to the horizontal flanges of the top and bottom frame members and welded thereto, bottom ribs of I section disposed with their ends abutting the lower ends of the side ribs and welded thereto, bottom, side and end wall panels disposed on the outer sides of the bottom, side and end ribs and with their edges in abutting relation to the bottom and top frame members and corner uprights and welded thereto, a cover comprising downwardly facing side and end frame members of angle section, a cover panel arranged on said frame members, and longitudinal and transverse reinforcing bars arranged on the outer side of said cover panel.

4. In a tank for impregnating materials, the combination of bottom frame side and end members of angled section disposed with their angles facing inwardly, top frame side and end members of angled section disposed with their angles facing outwardly, the top frame constituting a cover gasket seat, corner uprights extending between said top and bottom frame members, a plurality of side and end ribs of I section disposed in spaced relation with their ends in abutting relation to the horizontal flanges of the top and bottom frame members and welded thereto, bottom ribs of I section disposed with their ends abutting the lower ends of the side ribs and welded thereto, bottom, side and end wall panels disposed on the outer sides of the bottom, side and end ribs and with their edges in abutting relation to the bottom and top frame members and corner uprights and welded thereto, a cover comprising downwardly facing side and end frame members of angle section, a cover panel arranged on said frame members, longitudinal and transverse reinforcing bars arranged on the outer side of said cover panel, work supporting bars disposed transversely within said tank between opposed pairs of side ribs and with their ends secured thereto, said bars being arranged in an inclined series to support the material within the tank in an inclined relation therein, the side ribs constituting material abutment members, and a hold down member attached to the underside of said cover and projecting therebelow to engage work in said tank when said cover is closed.

5. In a tank for impregnating materials, the combination of bottom and top frames and corner uprights, the top frame constituting a cover gasket seat, a plurality of upright wall supporting ribs having their ends welded to said top and bottom frames, bottom ribs disposed with their ends abutting the lower ends of opposed upright ribs and welded thereto, bottom, side and end wall panels disposed on the outer sides of the bottom, side and end ribs welded thereto and to said bottom and top frame and corner uprights, a cover comprising a frame and a cover panel arranged thereon, reinforcing bars arranged on the outer side of the cover panel and secured thereto, hinge members carried by said tank top frame and having a swinging element extending slidably through said cover to form a slip connection to said cover whereby the cover is supported for swinging and for vertical movement relative to the top frame of the tank so that it is urged to closed position by atmospheric pressure when a vacuum is created within the

tank, and adjustable positioning studs on said cover coacting with said tank top frame to laterally position the cover on the tank.

6. In a tank for impregnating materials, the combination of bottom and top frames and corner uprights, the top frame constituting a cover gasket seat, a plurality of upright wall supporting ribs having their ends welded to said top and bottom frames, bottom ribs disposed with their ends abutting the lower ends of opposed upright ribs and welded thereto, bottom, side and end wall panels disposed on the outer sides of the bottom, side and end ribs and welded thereto and to said bottom and top frame and corner uprights, a cover, work supporting bars disposed transversely within said tank between opposed pairs of side ribs with their ends secured thereto, said bars being arranged in an inclined series to support the material within the tank in an inclined relation therein, the side ribs constituting material abutment members.

7. In a tank of the class described having bottom and side walls, reinforcing ribs for said bottom and side walls arranged therein in supporting relation to the bottom and walls, the wall supporting ribs constituting work abutments, work supporting bars arranged within said tank and supported by certain of the ribs thereof in an inclined series to support the material within the tank in an inclined relation therein, said tank being provided with a cover supporting jamb, the jamb being provided with a gasket, a cover adapted to close upon said gasket, and hinge members connecting said cover to said tank, one of the parts of each hinge member having a loose slidable connection to the cover whereby the cover is supported for swinging movement and for vertical movement relative to the tank so that it is urged to closed position by atmospheric pressure thereon when a vacuum is created within the tank.

8. In a tank of the class described having bottom and side walls, reinforcing ribs for said bottom and side walls arranged therein in supporting relation to the bottom and walls, the wall supporting ribs constituting work abutments, work supporting bars arranged within said tank in an inclined series to support the material within the tank in an inclined relation therein, said tank being provided with a cover supporting jamb, the jamb being provided with a gasket, and a cover adapted to freely seat upon said gasket so that the cover is urged to closed position by atmospheric pressure thereon when a vacuum is created within the tank.
